UNITED STATES PATENT OFFICE.

EDWIN G. WEISSMAN, OF EASTON, PENNSYLVANIA, ASSIGNOR, BY MESNE ASSIGNMENTS, TO INDIVIDUAL DRINKING CUP COMPANY, INC., OF EASTON, PENNSYLVANIA, A CORPORATION OF PENNSYLVANIA.

DISPENSING DEVICE.

Original application filed July 20, 1921, Serial No. 486,071. Divided and this application filed January 9, 1922. Serial No. 527,900.

The present invention relates to improvements in dispensing devices and more especially has to do with an improved closure and closure locking means, particularly 5 adapted for cup dispensing and like apparatus, this application being a division of my application filed July 20, 1921 Serial No. 486,071.

One object of the invention is to provide 10 an improved closure of a simple efficient nature adapted to be readily adjusted to opened and closed positions, and that when opened will occupy little space and be entirely out of the way.

15 Another object of the invention is to provide an improved closure of the character referred to having means for locking the same in opened and closed positions.

A further object of the invention is to 20 provide improved closure and closure locking means of simple, compact construction in the form of a single unit adapted to be detachably connected with the dispensing apparatus.

25 An important novel feature of the invention also resides in the provision of improved means for locking the cup container to the casing, and a common key control for said locking means and that for the closure.

30 The invention, with other objects and advantages thereof, and the particular construction, combinations and arrangements of parts comprising the same will be understood from the hereinafter contained detailed description, when considered in connection with the accompanying drawings, 35 forming part hereof, and illustrating one embodiment of the invention.

40 In the drawings:

Figure 1 is a side elevation of a cup dispenser equipped with improved closure and locking means in accordance with the present invention.

45 Figure 2 is a rear elevation of the apparatus without the closure and lock mechanism.

Figure 3 is a vertical section on an enlarged scale through the casing, the closure 50 being in open position.

Figure 4 is a transverse section on the line 4—4 of Figure 3.

Figure 4^a is a fragmentary transverse sec-

tion with the closure partially removed from the door casing. 55

Figure 4^b is a transverse section with the closure plate in locked position within the door casing.

Figure 5 is a side elevation with parts shown in section, the closure being in closed 60 position.

Figure 6 is a detail transverse section through the lock casing and the adjoining portion of the main casing for the apparatus. 65

Figure 7 is a side elevation of the lower portion of the container.

Figure 8 is a bottom plan view of the container.

Figure 9 is a detail section of part of the 70 locking mechanism for the container.

Figure 10 is a rear elevation of the lock casing, without the lock mechanism.

Figure 11 is a detail transverse section 75 through the main casing, the delivery mechanism being removed.

Figure 12 is a detailed view, on an enlarged scale, of the closure and locking means, parts being shown in plan and parts in section. 80

Figure 13 is a detailed side elevation of the pawls of the container locking means.

Figure 14 is a detail side elevation, with parts shown in section, of the operating shaft and key control of the locking means. 85

Figure 15 is a rear elevation of the lock plate.

Figure 16 is an end elevation of the lock plate.

Figure 17 is a top plan view of the closure plate. 90

Figure 18 is a side elevation of the closure plate.

While a specific embodiment of the invention is illustrated in the drawings, it will, of course, be understood that changes and variations of the particular construction illustrated, and the embodiment of the invention in other forms as will appeal to those skilled in the art and falling within the scope of the appended claims may be practiced without departing from the spirit of the invention. 95 100

The invention comprehends an improved closure, and supporting and locking means therefor comprising a casing part located at 105

one side of the main casing of the apparatus, and a door or closure plate connected with the casing part to provide for positioning the same within said casing part out of the 5 way and concealed from view, when not in use, and to be readily withdrawn from the casing part to a position to close the delivery opening thereof, with means for locking the closure plate both in its open and closed 10 positions.

Referring to a detailed description of the drawings, 1 designates a casing preferably of metal which forms a support for the cup container and the delivery mechanism. The 15 casing 1 which is shown as of general cylindrical form with substantially rectangular shaped extensions 2 at the front and rear, has integral flanges or bracket portions 3 adapted to be secured by screws 4 or the like 20 to any suitable support 5. Extending upwardly from the top of the casing 1 is a socket 6, in which the lower end of the cup container 7 is seated, the latter being preferably of glass and closed at its upper end 25 as shown. The cup container is provided at its lower end with a metal collar 8 and is detachably secured to the casing 1 by inclined faced lugs 9 and 10 on the collar and casing. At the lower part of the housing 30 is a tubular delivery part 11. In this particular instance the tubular part 11 is supported, as shown, for axial rotation on the bottom plate 1^a of the casing, said tubular part 11 being adapted to be turned to operate the cup delivery mechanism. The tubular part 11 is shown as having a restricted 35 throat portion 12 formed by tapering ribs 13 on the inner face thereof, and an inwardly extending annular lip or flange 14 at its lower end.

In the preferred embodiment of the invention illustrated in the drawings, the door casing part and locking means is shown in the form of a single unit detachably connected with the main casing for the cup delivery mechanism.

15 designates the casing or housing part for the closure, the same being shown substantially rectangular shaped, having front 50 and back wall 16—17, side walls 18—19, and top and bottom walls 20—21. The front wall 16 of the closure casing or housing has an opening 22 and a recess 23 in the front face thereof adapted to receive the rear rectangular extension 2 and attaching flanges 3 of the main casing 1, the parts being secured together by screws 24, the casing 1 with the door closure casing or housing part 15 attached thereto, being adapted to be secured to any suitable support by the screws 4. 25 designates the door or closure plate, said plate being adapted to be moved into and out of the casing part 15 through an opening 16^a in its front and bottom walls. 60 65 At its inner end the door or closure 25 has

trunnions 26, which project laterally and above the adjoining upper face of the plate, and are provided with flat upper face portions 26^a and rounded portions 26^b, the end faces of said trunnions slidably engaging 70 the side walls of the door casing part 15, and the flat face portions 25^a of the trunnions being adapted to slide over the inner face of the front plate 16 of the casing part, and the adjoining rear face portions of the 75 flanges 3. When the closure plate 25 is withdrawn from the door casing part, the trunnions 26 engage bearings 27 on the lower portion of the casing part, a hinged connection being thus afforded so that the closure plate may be swung upwardly to fit against and close the lower end of the tubular part 11. The door or closure plate 25 has on its upper face at its forward portion a cylindrical boss or projecting part 28, 80 which is adapted to fit nicely within the annular lip or flange 14 at the lower end of the tubular part 11 and the end of the closure plate 25 is semi-circular shaped to correspond with the curvature of the tubular 85 part 11. Extending forwardly from the cylindrical boss or projecting part 28 is a portion 29 adapted when the door or closure plate is in closed position, to rest upon the upper face of the flange 14, the closure 90 plate in its adjustment to closed position being swung upwardly and then drawn forwardly to engage the portion 29 over the annular flange 14. The portion 29 is notched, as shown, to fit between the ribs 100 13 on the interior of the tubular part and acts to lock the same against rotation. The front wall 16 of the door casing part 15 has a lower outwardly curved portion 30, and the rear face of the closure plate 25 is slightly 105 beveled at 25^a, so that when the plate is moved to open position within the casing part 15 it will fit closely against the front wall 16 of the casing part 15 with its rear face extending substantially vertically. 110 When the closure plate 25 is moved into the casing part 15, the trunnions 26 engage the curved portions 31 on the upper part of the casing part 15 and enter the recesses or seats 31^a in the adjoining flanges 3 of the casing 1. 115 The means for locking the door or closure plate 25 comprises a plate 32 arranged in the casing part 15 at the rear of the closure plate 25, and provided with a yoke 33 at its upper end engaging a crank or eccentric 120 125 on a transverse shaft 35 supported for rotation in the upper portion of the casing part 15. The lock plate 32 has guide ribs 36 and pairs of inclined face portions 37—38 on the rear face thereof at its upper and lower portions to cooperate with pairs of inclined portions 39—40, on the upper and lower portions of the rear wall of the casing part 15. The lock plate 32 is adapted to be supported by the transverse shaft 35 in an up- 130

per position (as indicated in Figures 4^a and 4^b of the drawings), with the inclined face portions 37—38 out of engagement with the inclined face portions 39—40, and out of engagement with the closure plate, so that the latter may be moved into or out of the casing part, and is free for movement to engage or disengage the same with the tubular part 11. By giving the operating shaft 35 a half turn in the direction of the arrow (see Figure 5 of the drawings), the lock plate 32 will be moved downwardly and laterally, the inclined face portions 37—38 engaging the inclined face portions 39—40 effecting a lateral shifting of the plate as the same is moved downwardly by the eccentric, the plate being moved to a position to engage and hold the closure plate within the casing, (as shown in Figure 4), or to hold the closure plate in its closed position (see Figure 5), in the latter case the lower end of the lock plate 32 engaging the inner end of the closure plate 25. By rotating the shaft 35 and another half turn in the direction of the arrow, the lock plate 32 will be moved by the eccentric upwardly and rearwardly out of engagement with the lock plate back to the position indicated in Figure 4^a of the drawings. The operating shaft 35, at one end is provided with a slot 46, and arranged to slide longitudinally therein is a lock pin 42, said pin 42 having a stem portion 42^a working in longitudinal bore 43 in the end of the shaft 35. 44 designates a coiled spring acting to force the lock pin 42 outwardly into engagement with a slot 45 of the casing part 15, the pin 42 being adapted to engage the slot and lock the operating shaft 35 against rotation when the lock plate 32 has been moved to its operative and inoperative positions. The lock pin 42 is adapted to be depressed out of engagement with the slot 45 in the casing part 15, and the shaft 35 rotated by a key 46^a adapted to be inserted through the slot 45, said slot extending to the exterior casing part 15. In combination with the closure locking means, means is also provided for locking the cup container 7 to the casing 1. The collar 8 at the lower end of the cup container is provided with a series of teeth 47. Cooperating with the teeth 47 are two pawls 48—49 arranged side by side and having teeth 48^a—49^a. 50—51 designates springs 55 which act to force the pawls 48—49 inwardly into engagement with the teeth 47 of the collar 8, each of said springs being secured at one end to the casing part 15 by a screw 52, and having their upper portions engaging notches 48^b—49^b in the inner ends of the pawls. The notches 48^b—49^b are of different depth and alternately arranged as shown, said pawls being adapted to operate independently of each other in engaging the teeth 47 of the collar 8. The pawls 48—49,

are provided with slotted portions 48^c—49^c to engage an eccentric portion 53 on the operating shaft 35, the eccentric portion 53 being adapted, when the shaft 35 is turned to move the lock plate 32 to inoperative position, to also retract the pawls 48—49 from engagement with the teeth 47 of the collar 8.

It will be noted that the special locking means for the closure and container is of a simple and efficient nature, and that a single key control serves for both locking means provision being made for locking the cup container to the casing when the apparatus is in use as well as when the door or closure plate is locked in closed position.

What I claim is:

1. In an apparatus of the class described, a casing having a delivery opening, a casing part extending along one side of the casing, a door to close the delivery opening, having a sliding pivotal connection at one end with the casing part, said door being adapted to be positioned within said casing part when opened and to be moved therefrom to closed position over the delivery opening, and means in the casing part for holding the door in open and closed positions.

2. In an apparatus of the class described, a casing having a delivery opening at one end, a door casing extending along one side of the first mentioned casing, means for detachably connecting the door casing with the first mentioned casing, and a door having a sliding connection with the casing, said door being adapted to be positioned within the casing and to be withdrawn therefrom to closed position over the delivery opening.

3. In an apparatus of the class described, a casing having a delivery opening at one end, a door casing extending along one side of the first mentioned casing, means for detachably connecting the door casing with the first mentioned casing, a door having a sliding connection with the casing, said door being adapted to be positioned within the casing and to be withdrawn therefrom to closed position over the delivery opening, and means within the casing for locking the door in its opened and closed positions.

4. In an apparatus of the class described, a casing having a delivery opening at one end, a casing part extending along one side thereof having an opening at one end, bearings on the casing part at opposite sides thereof at its lower end, and said casing part having recesses at opposite sides in its upper portion, a closure plate adapted to slide in the casing part and be withdrawn therefrom and swung to closed position over the delivery opening, said closure plate being provided with trunnions at opposite sides thereof at one end, said trunnions being adapted to pivotally engage the bear-

- 5   ings at the lower end of the casing part, said closure plate being adapted to be moved laterally within the casing part to engage the said recesses of the said casing part at the limit of the inward movement of the said closure plate, and means for shifting the closure plate laterally upon longitudinal movement thereof into the casing.
- 6   5. In an apparatus of the class described, a casing having a delivery opening at one end, a casing part extending along one side of the casing having an opening at one end, bearings at opposite sides of the casing part at one end thereof, the bearings having curved wall portions, and said casing part having flat wall portions at opposite sides thereof, a closure plate adapted to slide within the casing part and provided with trunnions at its inner end at opposite sides thereof to pivotally engage the bearings on the casing part, said trunnions having flat face portions at one side to engage the flat wall portions of the casing part, and having rounded surfaces to engage the said bearings, said closure plate being adapted to occupy a position within the casing part and to be moved therefrom into closed position over the delivery opening.
- 7   6. In an apparatus of the class described, a casing having a delivery opening at one end, a casing part at one side of the casing, a closure plate having a sliding pivotal connection at one end with said casing part, said closure plate being adapted to slide into the casing part and to be withdrawn therefrom and swung to closed position over the delivery opening, and means for holding the closure plate in its open and closed positions, said means including a member movable longitudinally and laterally of the casing part and adapted to engage the closure plate at one side thereof when the same is in open position and to engage an end portion of said plate when the same is in closed position, and operating means for said member.
- 8   7. In an apparatus of the class described, a casing having a delivery opening at one end, a casing part at one side of the casing, a closure plate having a sliding pivotal connection at one end with said casing part, said closure plate being adapted to slide into the casing part and to be withdrawn therefrom and swung to closed position over the delivery opening, and means for holding the closure plate in its open position, said means including a plate movable laterally of the casing and adapted to engage the closure plate at one side thereof when the same is in open position, and operating means for said plate.
- 9   8. In an apparatus of the class described, a casing having a delivery opening at one end, a casing part at one side of the casing, a closure plate having a sliding pivotal connection at one end with said casing part, said closure plate being adapted to slide into the casing part and to be withdrawn therefrom and swung to closed position over the delivery opening, and means for holding the closure plate in its open position, said means including a plate movable laterally of the casing and adapted to engage the closure plate at one side thereof.
- 10   9. In an apparatus of the class described, a casing having a delivery opening at one end, a casing part at one side of the casing, a closure plate having a sliding pivotal connection at one end with said casing part, the closure plate being adapted to slide into the casing part and to be withdrawn therefrom and swung to closed position over the delivery opening, and means for holding the closure plate in its open and closed positions, said means including a plate movable longitudinally and bodily shiftable laterally of the casing, and operating means for said plate including a cam surface on one of said parts engaging a portion on the other part acting to move the plate laterally when moved longitudinally in one direction.
- 11   10. In an apparatus of the class described, a casing having a delivery opening at one end, a casing part at one side of the casing having a side wall provided with a recess in the inner face thereof, a closure plate slideable within the casing, the closure plate being adapted to occupy a position within the casing and to be withdrawn therefrom to closed position over the delivery opening, and said closure plate being adapted to be moved laterally of the casing and having a portion to engage the said recess at the limit of its inward movement, and means for holding the closure plate in its open position within the casing part with said portion in engagement with the said recess including a plate movable longitudinally and laterally of the casing, said plate being adapted to engage the closure plate at one side thereof, and operating means for said plate.
- 12   11. In an apparatus of the class described, a casing having a delivery opening at one end, a door casing extending along one side of the first mentioned casing, a door having a sliding pivotal connection at one end with the casing, the door being adapted to be positioned in the casing part and to be withdrawn therefrom in closed position over the delivery opening, and means for holding the door in its open and closed positions, said means including a lock plate movable longitudinally of the casing and adapted to engage the closure plate at one side thereof.

a transversely disposed rotary operating shaft having an eccentric part thereon, and a part on said plate engaging the eccentric.

12. In an apparatus of the class described, a casing having a delivery opening at one end, a door casing extending along one side of the first mentioned casing, a door having a sliding pivotal connection at one end with the door casing, the door being adapted to be positioned within the door casing and to be withdrawn therefrom in closed position over the delivery opening, and means for holding the door in its open and closed positions, said means including a locking plate movable longitudinally of the door casing and adapted to engage the closure plate at one side thereof, a transversely disposed rotary operating shaft having an eccentric part thereon, and a yoke on said plate engaging the eccentric, and cooperating inclines on said plate and casing adapted to shift the plate laterally when the same is moved longitudinally in one direction by the eccentric.

13. In an apparatus of the class described, a casing having a delivery opening at one end, a door casing extending along one side of the first mentioned casing, a door having a sliding pivotal connection at one end with the door casing, the door being adapted to be positioned in the door casing and to be withdrawn therefrom in closed position over the delivery opening, and means for holding the door in its open and closed positions, said means including a locking plate movable longitudinally of the door casing and adapted to engage the closure plate at one side thereof, a transversely disposed rotary operating shaft having an eccentric part thereon, and a yoke on said plate engaging the eccentric, and key operated locking means for the shaft at one end thereof.

14. In an apparatus of the class described, a casing having a delivery opening at one end, a door casing extending along one side of the first mentioned casing, a door having a sliding pivotal connection at one end with the door casing, the door being adapted to be positioned in the door casing and to be withdrawn therefrom in closed position over the delivery opening, and means for holding the door in its open and closed positions, said means including a locking plate movable longitudinally of the door casing and adapted to engage the closure plate at one side thereof, a transversely disposed rotary operating shaft having an eccentric part thereon, and a yoke on said plate engaging the eccentric, and a longitudinally movable key operated locking pin on one end of said shaft adapted to engage a slot in the casing part.

15. In an apparatus of the class described, a casing having a delivery opening at one end, a casing part extending along one side

of the casing open at its lower end, said casing part having bearings at opposite sides at its lower end and having recesses in the inner face of its front wall at the upper portion thereof, a closure plate adapted to slide within the casing part, the closure plate being adapted to occupy a position within the casing part and to be withdrawn therefrom in closed position over the delivery opening, said closure plate having trunnions at its inner end at opposite sides thereof, the trunnions being adapted to pivotally engage the bearings on the casing part when the closure plate is withdrawn therefrom, and to engage the recesses in the front wall of the casing part when moved into the same, and a member movable longitudinally of the casing part and adapted to engage the closure plate at one side thereof and hold the same within the casing part.

16. In an apparatus of the class described, a casing having a delivery opening and a socket part, a cup container detachably seated in said socket, a door casing extending alongside of the first mentioned casing, a door having a sliding pivotal connection at one end with the door casing, the door being adapted to be positioned within the door casing and to be withdrawn therefrom in closed position over the delivery opening, and key operated means for locking the door in its open and closed position, and also for locking the cup container in said socket, said last mentioned means including a rotary operating shaft, a locking member operatively connected with the shaft and adapted to engage and hold the door, and a pawl operatively connected with said shaft and adapted to engage and lock said container.

17. In an apparatus of the class described, a casing having a delivery opening and a socket part, a cup container detachably seated in said socket, a door casing extending alongside of the first mentioned casing, a door having a sliding pivotal connection at one end with the door casing, the door being adapted to be positioned within the door casing and to be withdrawn therefrom in closed position over the delivery opening, and key operated means for locking the door in its open and closed position, and also for locking the cup container in said socket, said last mentioned means including an operating shaft, a locking member operatively connected with the shaft and adapted to engage and hold the door, and a pawl slidably mounted within the casing and having a yoke portion at its inner end engaging an eccentric part on said shaft, said pawl being adapted to engage and lock the container.

18. In an apparatus of the class described, a casing having a delivery opening and a socket part, a cup container detachably seated in said socket, a door casing extending alongside of the first mentioned casing,

a door having a sliding pivotal connection at one end with the door casing, the door being adapted to be positioned within the door casing and to be withdrawn therefrom
5 in closed position over the delivery opening, and key operated means for locking the door in its open and closed position, and also for locking the cup container in said socket, said last mentioned means including a rotary
10 operating shaft, a locking member operatively connected with the shaft and adapted to engage and hold the door, and a plurality of pawls connected with the shaft to operate independently of each other to engage
15 and lock said container.

19. In an apparatus of the class described, a vertically extending casing having a delivery opening at one end, a casing part extending along one side of the first mentioned
20 casing having its lower portion spaced from the lower end portion of the casing, a door having a sliding pivotal connection at one end with the casing part, said door being adapted to be positioned within said casing
25 part and to be moved therefrom in closed position over the delivery opening.

20. In an apparatus of the class described, a casing having a delivery opening, and a socket part, a cup container detachably seated in the socket part, a door to close the delivery opening, said door being connected with the casing for movement to a position over the delivery opening, and to a position along one side of the casing, and means for
30 locking the door in open position, and also for locking the cup container in the socket, said means including a rotary shaft, a locking member operatively connected with the shaft and adapted to engage and hold the
35 door, and a locking member operatively associated with the shaft to lock said container.

21. In an apparatus of the class described, a casing having a delivery opening and a socket part, a cup container detachably seated in the socket, a door to close the delivery opening, said door being connected with the casing for movement to a position over the delivery opening and to an open position along one side of the casing, and means for
45 locking the door in open position, and also for locking the cup container in the socket part, said means including a rotary shaft having an eccentric part thereon, a locking member operatively connected with the shaft and adapted to engage and hold the closure plate, and a pawl having a yoke part engaging the eccentric part of the operating shaft and adapted to engage and lock the container.

22. In an apparatus of the class described, a casing having a delivery opening and a socket part, a cup container detachably seated in the socket part, a door to close the delivery opening, said door being connected
55 with the casing for movement to a position

over the delivery opening, and to a position along one side of the casing, and means for locking the door in open position, and also for locking the cup container in the socket, said means including a rotary shaft having
60 an eccentric part thereon, a locking member operatively connected with the shaft to engage and hold the closure plate, a pawl having a yoke part engaging the eccentric part of the operating shaft and adapted to engage and lock the container, and a spring acting to force the pawl in one direction to engage the container.

23. In an apparatus of the class described, a casing having a delivery opening at one end, a casing part extending along one side thereof having an opening at one end, bearings on the casing part at opposite sides thereof at its lower end and said casing having recesses at opposite sides in its upper portion, a closure plate adapted to slide within the casing part and to be withdrawn therefrom and swung to closed position over the delivery opening, said closure plate being provided with trunnions at opposite sides thereof at one end, said trunnions being adapted to pivotally engage the bearings at the lower end of the casing part, and said closure plate being adapted to be moved laterally within the casing part to engage the said recesses of the said casing part at the limit of the inward movement of the said closure plate, and means for shifting the closure plate laterally upon longitudinal movement thereof into the casing, said means comprising cam portions on the casing adjacent the said recesses.

24. In an apparatus of the class described, a casing having a delivery opening at one end, a casing part at one side thereof, a closure plate having a sliding pivotal connection at one end with the casing part, said closure plate being adapted to occupy a position within the casing part, and to be withdrawn therefrom and swung to closed position over the delivery opening, and means for holding the closure plate in open position, said means including a member movable in the casing part and adapted to engage the closure plate at one side thereof, and operating means for said member.

25. In an apparatus of the class described, a casing having a delivery opening at one end, a casing part at one side thereof, a closure plate having a sliding pivotal connection at one end with the casing part, said closure plate being adapted to occupy a position within the casing part and to be withdrawn therefrom and swung to closed position over the delivery opening, and means for holding the closure plate in its open and closed positions, said means including a plate member movable within the casing part, said plate member being adapted to engage the closure plate at one side thereof, when the

closure plate is in open position and to engage an end portion of the closure plate when the same is in closed position, and operating means for said plate member.

26. In an apparatus of the class described, a casing having a delivery opening at one end, a casing part at one side thereof, a closure plate having a sliding pivotal connection at one end with the casing part 10 said closure plate being adapted to occupy a position within the casing part and to be withdrawn therefrom and swung to closed position over the delivery opening, and means 15 for holding the closure plate in open position, said means including a plate movable

longitudinally and laterally of the casing part, the plate being adapted to engage the closure plate at one side thereof, and operating means for said plate, said operating means including a rotary shaft, an eccentric 20 part on the shaft, a yoke portion on the plate engaging the eccentric, and cooperating cam faces on the casing part and said plate to shift the latter laterally upon movement of the same longitudinally in one direction by 25 the rotary shaft.

In testimony whereof I hereunto affix my signature.

EDWIN G. WEISSMAN.
